UNITED STATES PATENT OFFICE.

JOHN F. NETTLE, OF BUTTE, MONTANA, ASSIGNOR OF ONE-HALF TO SAVIN LISA, OF BUTTE, MONTANA.

CUSHION-WHEEL.

1,143,304.

Specification of Letters Patent. Patented June 15, 1915.

Application filed November 18, 1914. Serial No. 872,773.

To all whom it may concern:

Be it known that I, JOHN F. NETTLE, a citizen of the United States, residing at Butte, in the county of Silver Bow and State 5 of Montana, have invented certain new and useful Improvements in Cushion-Wheels, of which the following is a specification, reference being had to the accompanying drawings.

10 My invention relates to vehicle wheels, and particularly to wheels designed for use on automobiles and like vehicles.

15 The main object of my invention is to provide a wheel particularly adapted for heavy service, and in which there shall be relatively great resilience.

20 A further object of the invention is to form the wheel so that the parts thereof may be readily assembled or disassembled in case of repairs being needed.

25 A further object is to provide a wheel having a plurality of sets of cushioning members so arranged that the exterior series of cushioning members will take up the lighter jolts and shocks to which the wheel is likely to be subjected, while both series of cushioning members will be actuated by and will cushion jolts or shocks of a severe nature.

30 A further object of the invention is to so form the wheel that it will resist lateral strains.

35 Another object of the invention is to provide means for preventing dust, dirt or grit from passing into the interior of the wheel.

Other objects will appear in the course of the following description.

My invention is illustrated in the accompanying drawings, wherein—

40 Figure 1 is a side elevation of a wheel embodying one form of my invention, one of the casing plates of the wheel being broken away to show the interior construction; Fig. 2 is a diametrical section of the wheel shown in Fig. 1; Fig. 3 is a detail view showing the manner in which one of the coiled springs is supported at its ends; Fig. 4 is a side elevation of another form of wheel, the exterior casing being partly

45 broken away so as to show the interior of the wheel; Fig. 5 is a fragmentary diametrical section through the wheel; Fig. 6 is a detail longitudinal section of a portion of one of the cushioning members.

50 Corresponding and like parts are referred

to in the following description and designated in all parts of the drawings by like reference numerals.

Referring to Figs. 1, 2 and 3, it will be seen that the wheel comprises in this case a hub portion 2 which is adapted to rest upon and be carried by the axle 3 and rotate either with or upon this axle. The hub portion is formed with a central radially extending body 4 and a base from which the body extends, this base being cut away to form two steps 5 and 6.

60 Mounted upon the steps 6 and abutting against the shoulders formed by the steps 5 are the annular hub rings 7, each of which is formed with a flanged base adapted to be attached in any suitable manner to the hub 2, as by means of screws. It will of course be seen that the inner faces of the hub rings 70 are spaced from the adjacent faces of the body 4 of the hub.

65 Disposed on each side of the body 4 of the hub are the annular plates 8, these plates being spaced from each other and having their inner margins disposed between the hub rings 7 and the body 4 of the hub for sliding movement. The outer margins of these plates are disposed on each side of and in sliding engagement with a felly 9. This felly has a width equal to the space between the plates 8, and has an outer relatively wide portion 10 to which a tread or 75 tire 11 may be attached in any suitable manner. The outer side faces of the widened or tread portion 10 of the felly are cut away to provide recesses in which are disposed the outer margins of the felly plates 12, these felly plates being held in position 80 against the felly by means of stud bolts 13. It will of course be noted that the outer 90 margins of the plates 8 have free sliding movement between the body of the felly and the plates 12.

85 Disposed between the inner and outer margins of the annular plates 8 is an abutment ring 14. This ring as illustrated in Fig. 2, is preferably hollow, and the inner and outer faces of the ring are channeled. The ring is provided with transverse bolt holes for the reception of bolts 15 which pass 100 through the plates 8 and through the ring and hold the ring securely in place. As illustrated, there are three series of these bolts. Thus this ring 14 is held rigidly to the plates 8 and is movable therewith.

Disposed between the felly 9 and the abutment ring 14 is a series of cushioning springs 16. Any inward movement of the felly will compress these springs 16 and any outward movement of the felly with relation to the hub will expand the springs. The ends of the springs are held respectively to the abutment ring 14 and to the felly 9 by bifurcated or forked pins 17, between the forks of which the ends of the springs are placed, as illustrated in Fig. 3, a transverse pin or bolt 18 being passed through the bifurcated or forked extremity of the pin 17 and through the end of the spring. I do not wish to limit myself, however, to this manner of connecting the ends of the springs to the felly and abutment ring.

Likewise disposed between the abutment ring and the hub 4 are a plurality of springs 19 whose ends are attached respectively to the hub 4 and to the abutment ring by forked or bifurcated pins 17 as heretofore described.

In order to prevent the passage of dirt, dust or grit into the spring containing chambers, I preferably provide on each side of the felly the ring plates 20 which bear against the inner faces of the plates 8. Preferably the sides of the felly are recessed for the reception of the plates 20 and also formed with chambers in which are disposed the springs 21, these springs acting to urge the plates 20 outward and into close contact with the inner faces of the plates 8. A pair of these protecting dust rings designated 22 are also disposed in recesses upon the outer faces of the hub 4 adjacent the inner margins of the plates 8, these plates being forced outward and against the inner faces of the plates 8 by means of the coiled springs 23.

Where the wheel illustrated in Figs. 1, 2 and 3 is to be used as a driving wheel, I attach to those plates 12 which are disposed upon the one face of the wheel, the pulley ring 24 by which power may be transmitted to the wheel.

The operation of this form of my invention will be understood from what has gone before. The object of arranging the two series of springs in the manner shown is to distribute the load and the shock to the top and bottom portions of the wheels simultaneously and prevent the springs from swaying too much while the wheel is revolved, the clips or forked pins 17 which engage these springs holding the springs securely in place, but permitting expansion or contraction. The load and shock will compress both series of springs below the axle and will expand the springs above the axle; thus while the springs below the axle are resisting the load and shock by compression, the springs above the axle are sup-

porting the axle from the upper portion of the wheel. The annular hub plates 7 are for the purpose of resisting lateral strains and thrusts in conjunction with the side plates 8. These side plates 8 also prevent the felly 70 from moving laterally with relation to the wheel. The series of plates 12 fastened to the sides of the felly are for the purpose of preventing any tendency of the felly to pry open the side plates 8.

The other form of my invention illustrated in Figs. 4, 5 and 6 is in many respects similar to the form illustrated in Figs. 1 to 3. This form of wheel comprises a hub portion designated 25, which comprises a base 80 and a medially disposed radially extending body 26. The base is recessed or stepped for the reception of the oppositely disposed hub rings 27, which in this instance are connected to each other and to the hub by 85 means of the transverse bolts 28. These plates 27 are spaced from the side faces of the body 26 a sufficient distance to admit therein the side plates 29. Entrance of grit or dirt between the side plates and the side 90 faces of the body of the hub is prevented by means of the dust rings 30 which are disposed against the side faces of the hub body 26 and are urged outward against the inside faces of the side plates 29 by means 95 of springs 31 contained in recesses in the body portion of the hub. It is to be noted at this point that the circumference of the hub is slightly concaved transversely.

Disposed between and holding the side 100 plates in spaced relation and rigidly connected is the abutment ring 32. This abutment ring has its opposite faces concavely curved transversely, and is held to the side plates by means of transversely extending 105 bolts 33. There are two series of these bolts.

The felly of the wheel has a medially disposed inwardly extending body portion 34 and a relatively wide tread portion 35 to 110 which the tire 36 will be attached. This body portion 34 is narrower than the space between the plates 29, and disposed between the outer faces of the body portion 34 and the margins of the plates 29 are the dust 115 rings 36 urged outward against the faces of the plates 29 by means of springs 37. Disposed on each side of the tread of the felly and supported against shoulders formed in the side margins of the tread 120 portion are the rings 38 which overlap the outer margins of the plates 29 and are held in position by the transverse bolts 39.

Disposed between the abutment ring 32 and the hub, and bearing against the concaved faces of the hub body and the ring 32 is a cushioning element 40 which has the form of a cylindrical ring.

While I do not wish to limit myself to any particular form of ring or cushioning 130

element, I preferably form it with a plurality of interior chambers 41, these chambers being preferably spherical in form.

Disposed between the abutment ring and the body portion 34 of the tread element is the cushioning ring 42, which is preferably constructed in the same manner as the cushioning element 40.

A drive pulley 43 may be attached to one of the ring plates 38, while a drive pulley 44 may be attached to one of the side plates 29 by the bolts 33 which pass through the abutment 32.

The operation of the wheel shown in Figs. 4 and 5 will be obvious from what has gone before. Shocks delivered to the wheel or loads upon the axle will be supported by means of the cushioning elements 40 and 42 in case of relatively light shocks. The cushioning element 42 will probably receive most of the shock, but in case of a load upon the axle it is obvious that both of the cushioning elements will be put in action and the strain and load distributed.

In the operation of my wheel the slideable side plates 8 are to take lateral strains and will slip circumferentially only to that extent permitted by the springs 16 and 19. The wheel will not be rendered less operative, however, because of the slippage of these side plates. When the wheel shown in Figs. 1 and 2 is used as a driving wheel the power should be transmitted to the felly of the wheel, thus relieving the springs 16 and 19 from strains caused by the propelling force. If power is applied to hub or to the slideable side plates 8, this power will be transmitted to the felly by the spring. In the construction shown in Figs. 4 and 5 it is preferred that the power shall be transmitted to the felly instead of to the hub when the wheel is used as a driving wheel. If power is transmitted to the hub the tendency of the inner resilient member 42 will be to slip with the hub unless very heavily loaded. This tendency to slip is reduced to a minimum when the power is transmitted to a point beyond or at the periphery of the resilient member 40, or when the power is conveyed to the abutment ring. When the power is conveyed to the felly slipping of

the members within the felly will not cause a loss of power. In fact, the slipping of the members will be practically nil. The slideable side plates are not intended for the purpose of taking circumferential strains but lateral strains. The purpose of the abutment ring in both forms of my invention is to support the slideable side plates and with the inner resilient means to form a resilient hub. A further purpose is to divide the two different sets of resilient members so that if one set should be damaged by any means the wheel would not become entirely non-resilient. A further purpose is to form annular chambers between the side plates, the hub and the felly for the purpose of holding and containing the resilient members.

It is to be noted that the springs 16 and 19 have their ends pivoted to the studs 17 in such manner that the ends of the springs extend parallel to the plane of the wheel. This is to permit a certain pivotal movement of the springs in line with the direction of travel and thus prevent their ends from snapping off by the downward thrust of the hub.

Having described my invention, what I claim is:

A wheel of the character described including a hub, a felly arranged in spaced relation with the hub and including a substantially wide tread portion and an inwardly disposed portion, the inwardly disposed portion being of lesser width than the tread portion, annular flanges arranged upon the opposite faces of the hub and tread portion of the felly, annular plates arranged for vertical movement between the flanges and the outer faces of the hub and the inwardly disposed portion of the felly, the hub and tread portion of the felly constituting stops to limit the vertical movement of the plate in either direction, and cushioning means engaging the hub and felly.

In testimony whereof I hereunto affix my signature in the presence of two witnesses.

JOHN F. NETTLE.
